UNITED STATES PATENT OFFICE

EDWARD GRAY, OF DETROIT, MICHIGAN, ASSIGNOR TO EDWARD GRAY, ENGINEER, INC., OF DETROIT, MICHIGAN, A CORPORATION OF MICHIGAN

BOAT CONSTRUCTION

Application filed February 24, 1931. Serial No. 517,875.

This invention relates to certain new and useful improvements in metal boat building construction and has for its object to make an all-metal boat from rolled plate or sheets 5 of metal as they come from the mill, which may be cut up on the job as required for use and welded up as the work progresses, the keel and ribs being cut up from suitable stock and used as the forms for building up the 10 hull and plating up the same as the various longitudinal stringers are inserted.

A further object of the invention is to make a strong, tight and seaworthy craft in which all the seams are welded and a smooth exterior 15 hull construction secured, the longitudinal stringers acting as the spacing members for the plate which has been cut to longitudinal strips to form a planking.

The invention further consists in the arrangement and combination of the various parts which go to make up a complete boat 20 hull, as more fully hereinafter described and shown in the accompanying drawings, in which—

25 Figure 1 is a plan view of a boat built in accordance with my invention;

Fig. 2 a side elevation thereof;

Fig. 3 a transverse section on the line 3—3 of Fig. 2;

30 Fig. 4 a perspective view of the after-part of the hull showing the same in section to show the interior construction;

Fig. 5 an enlarged view showing in detail 35 the method of welding the parts together, and

Fig. 6 a modified construction of lap seam joint.

As shown in the drawings, A indicates the 40 keel, B the stem, C the transom of a boat. D are the ribs which are cut out from ordinary plate or bar stock and butted against the keel, in the usual practice of boat building.

E are the garboard strakes on opposite 45 sides of the keel A which projects sufficiently below the ribs to permit the upper edges of the strakes to butt against the keel to form a convenient joint for welding the strakes together. The ribs D are spaced apart a sufficient distance to form, along with the 50 stem, keel, and transom of the boat, the form

on which the metal plate or planking can be built up from the keel to the gunwale, beginning with the garboard strakes E after which the longitudinal stringers F are put in place between the ribs and permitted to 55 project slightly below the same so that the next longitudinal plates or planking G may abut against the same to form a proper welding seam which can be filled up flush with the welding material E'. The plating or 60 planking with alternate longitudinal strips is continued in this manner and the boat hull built up until the covering board H is reached and the hull closed in.

It will thus be seen that as each longitudinal plate is bent or laid up on the form the short sections of the longitudinal stringers are interposed between to form a shoulder for the next adjacent plate to butt up against and at the same time form a suitable joint for 70 welding, which may be filled up with the welded material to form an integral section and can be ground off to form a smooth joint; all the joints in the entire hull being welded, that is, the ribs to the plate, the longitudinal 75 stringers to the ribs, and to the adjacent plates respectively, the stringers forming the spacing medium for the plates as the boat is planked up, sufficient welding material being used to fill up all the joints flush.

It is apparent that with a construction of 80 this kind, the entire boat may be readily built from stock material which may be cut out as required for use, no special stock being required other than that of proper strength 85 and thickness, the plates not being difficult to bend to the form of the hull and thereby dispensing with the necessity of rolling or forging the plates to form from a templet as in ordinary iron or steel ship-building. The 90 construction is such that a boat may be built along these lines with an acetylene torch for cutting the plates from stock sheets and a welding apparatus to weld the plates to the 95 ribs, keel and stringers, as the boat is being built up plate by plate, from the keel up, the longitudinal stringers being interposed as desired to form the necessary welding seams and to strengthen the hull as required.

It will thus be seen that with an iron or 100

metal hull construction of this kind, it is possible to build a very strong hull at a minimum expense from stock sheets of metal, requiring no special plant equipment as in the ordinary metal shipyards now in use, and that by reason of using the welded joints at all points where a seam occurs, a very strong and tight hull is secured, the extruded metal at the welded joint along the seams in the longitudinal plating of the hull being afterwards ground or polished off to form a perfectly smooth joint.

Another advantage of this construction is that the keel and frame work of the hull formed by the ribs, deck, beams and transom make a form upon which the boat can be completely plated, these parts themselves forming an integral part of the boat structure which would not have to be removed as in the ordinary practice of boat building where wooden forms are used, thus effecting a saving in this regard.

In Figure 6, I have shown a modified construction of lap seam joint in which the adjacent plates I are spaced apart by the projections J struck up from the lap seam member K. The projections J are used merely to space the adjacent plates I and extend into the space only enough to serve this purpose. Likewise, in the construction shown in Figures 1 to 5, the longitudinal members extend into the spaces between adjacent plate members only enough to be engaged and spaced thereby. No substantial surface engagement of the longitudinal members by the plates is necessary and in fact is not desired, inasmuch as it reduces the area of the surfaces exposed for welding.

It will also be understood that the joints herein disclosed, although shown and described in connection with boat building, are also capable of general usage as in the construction of walls, bulwarks, water gates and the like.

Although specific embodiments of the invention have been illustrated and described it will be understood that various alterations in the details of construction may be made without departing from the scope of the invention as indicated by the appended claims.

What I claim is:—

1. A boat bottom comprising a longitudinal keel member, unitary ribs secured to opposite sides thereof and extending in opposite directions thereof, longitudinal stringers secured to and between said ribs and extending substantially parallel to said keel member, plates inserted between said longitudinal members engaging the lower surfaces of said ribs, said plates extending continuously and integrally from bow to stern adjacent plates having their confronting surfaces partially in contact with opposed surfaces of said longitudinal members to be spaced there-

by, and welding material filling the spaces between adjacent plates.

2. The method of building a boat bottom including the steps of laying a keel member to extend from opposite sides thereof, securing ribs transversely of said keel member to extend from opposite sides thereof, placing the edges of two bow-to-stern plate members partially into contact with opposed surfaces of said keel member and in contact with the lower surfaces of said ribs, such that said keel member spaces the plate members apart and partially fills the space therebetween, filling the remainder of said space by arc welding, laying longitudinal members against the remaining edges of said plate members to partially cover said edges, laying additional plate members against the outer surfaces of said longitudinal members, such that their edges are partially covered by said sides and said longitudinal members serve to space adjacent plate members apart without filling the space therebetween, and filling the remainder of said spaces by arc welding.

3. The method of building a boat bottom including the steps of laying a keel member, securing ribs transversely of said keel member to extend from opposite sides thereof, welding longitudinal stringers in sections to and between said rib members, and welding bottom bow-to-stern plates to the lower edges of said ribs and stringer sections in the spaces defined thereby.

In testimony whereof I affix my signature.

EDWARD GRAY.
